[57] **CLAIM**

The ornamental design for portable electric circular saw, as shown.

DESCRIPTION

FIG. 1 is a perspective view of a portable electric circular saw showing our new design;

FIG. 2 is a front view of FIG. 1;

FIG. 3 is a plan view of FIG. 1;

FIG. 4 is a left side view of FIG. 1;

FIG. 5 is a right side view of FIG. 1;

FIG. 6 is a rear view of FIG. 1; and,

FIG. 7 is a bottom view of FIG. 1.

FIG. 1

FIG. 2

FIG. 3

FIG. 4

FIG. 5

*FIG. 6**FIG. 7*
